UNITED STATES PATENT OFFICE.

HARRY W. McKEE, OF CINCINNATI, OHIO.

MOVING IMPLEMENT.

1,271,594.

Specification of Letters Patent.

Patented July 9, 1918.

Application filed August 23, 1915. Serial No. 46,932.

To all whom it may concern:

Be it known that I, HARRY W. McKEE, a citizen of the United States, residing at Cincinnati, in the county of Hamilton and State 5 of Ohio, have invented certain new and useful Improvements in Moving Implements, of which the following is a specification.

It is the object of my invention to provide an implement arranged for engagement with a load, for instance a packing box, 10 crate, or other object, for lifting the same, or for shifting the same upon the floor, depending on the point of contact with the load and the direction in which the force of 15 the moving member is applied.

I have exemplified my improved device as applied for lifting a box and also for lifting a crate, from which representations its 20 application in other relations may be readily perceived.

My improved device is intended for lifting very heavy loads, and is compactly arranged, and so constructed as to enable great power to be applied, and for maintaining 25 the members in moved relation for preventing accidental retraction of the same.

The invention will be further readily understood from the following description and claim, and from the drawing, in which lat- 30 ter:

Figure 1 is a side elevation of my improved device, shown applied for lifting a large packing case.

Fig. 2 is a side elevation of the same, 35 showing the packing case in lifted relation with a moving roller thereunder, the moving bar being partly broken away.

Fig. 3 is a front elevation of my improved device with the socket for the moving bar 40 partly broken away.

Fig. 4 is a central vertical section of the same taken on the line 4-4 of Fig. 3.

Fig. 5 is a plan view of my improved device with the moving bar removed.

Fig. 6 is a cross-section of the same taken 45 on a line corresponding to the line 6-6 of Fig. 4.

Fig. 7 is a bottom perspective view of the lower portion of my improved device; and, 50 Fig. 8 is a side elevation of my improved device showing the same applied for moving a crate.

11 represents the housing of my improved device, in which a moving member, shown 55 as a slide 12, is arranged to slide. The housing comprises a front wall 13, from

which sides 14 project rearwardly, the rear ends of said walls being provided with rearwardly and inwardly projecting wings 15, the construction forming a guiding channel 60 16 extending lengthwise of said housing. The housing is provided at its lower end with lateral extensions 17, the sides of the housing conforming to the shape of said extensions and strengthening the same. The 65 housing also has a bottom wall 20 provided with a large number of projections 21 projecting downwardly from said bottom wall for forming a roughened surface which finds ready lodgment on the floor or other surface 70 against which said bottom wall is placed, holding said bottom wall in place without injury to the floor or other object and preventing shifting of the housing.

The moving member has a rear wall 24 75 and is provided with side flanges 25 extending longitudinally thereof, and projecting forwardly in a direction opposite to the direction in which the sides 14 extend, for forming a longitudinal space 26 between the 80 front wall of the housing and the rear wall of the slide. The rear edges of the side flanges of the slide are provided with rearwardly and inwardly projecting slanting faces 28 arranged to engage the forward 85 faces of the rearwardly and inwardly projecting wings 15 for maintaining the moving member in the housing.

The front face of the rear wall 24 of the slide is provided with a tooth-rack 29 ex- 90 tending longitudinally of said slide, the teeth projecting forwardly and crosswise of the slide.

The upper end of the slide is provided with an upwardly and rearwardly curved 95 upper end 31, provided with a plurality of teeth 32 arranged crosswise of the upper end of said slide, for engagement with the object to be moved, for instance, a packing case, illustrated at 33 in Figs. 1 and 2. These 100 teeth are arranged to embed themselves in the wood of the case for forming a hold upon said case.

The moving member is further provided at its lower end with a rearwardly extending shelf 36 preferably formed with a brace 105 37 thereunder connecting with the moving member.

For moving the moving member the housing is provided with forwardly extending 110 separated lugs 41 having a slot 42 between them. A segment-gear 43 is pivoted on a

pin 44 supported in bearings 45 of said lugs. The teeth of said segment-gear are arranged to project through said slot into engagement with the teeth of the rack 29. The 5 segment-gear is provided with a socket extension 47 integral therewith, in which a moving bar 48 is arranged to be seated, a pin 49 holding the bar in the socket.

The housing 11 is provided with a cross-10 girt 51 integral therewith for connecting the upper ends of the sides of the housing and insuring rigidity. The upper end of the housing at said cross-girt is provided with upwardly extending separated lugs 52, forming bearings for a pin 53, on which an upwardly and rearwardly extending pawl 54 is pivoted, the pawl being received in the channel between the sides flanges 25 of the slide 12 into engagement with the rack-teeth 15 provided for the purpose of coaction with the segment-gear.

Referring to Figs. 1 and 2, it will be noted that, when it is desired to lift an object, the housing and moving member are 20 placed slantingly with relation to the side of said object, and that the bottom of the housing is in a plane extending at an acute angle with relation to the longitudinal axis of the housing, so that when said housing 25 and lifting member are slantingly placed, as stated, the bottom of the housing will be parallel with the floor so as to have support on the floor over a comparatively large area, thereby preventing injury to the floor.

30 The depression of the moving bar 48 causes raising of the lifting member for raising the packing case, for the purpose, for instance, of inserting a roller, shown at 35 56, under said packing case. As the bar is lowered and the lifting member raised, the teeth 32 indent the object to be moved, embedding themselves therein to get a firm hold upon the object, and then raising the object. The pawl 54 engages successive teeth 40 45 passing the pawl for preventing accidental retraction of the lifting member or slide.

If it is desired to release the device, a slight depression of the bar 48 will permit the release of the pawl, and for enabling 50 55 ready release of the pawl to be had, I provide the same with a rearwardly and upwardly extending heel 57 upon which the foot may be placed for retracting the pawl, whereupon raising of the bar 48 is permitted for allowing the weight of the packing case to be received upon the roller and for releasing the device.

When it is desired to raise an object with 60 which the teeth 46 would not be liable to make secure contact, the shelf 36 is received under a portion of the object to be raised,

as under the cross-piece 58 of a crate, the cross-piece for instance being upon skids 59 and in sufficiently raised position for permitting insertion of the shelf 36 thereunder. 65

The direction of movement of the object to be moved will be longitudinal with relation to the sliding movement of the slide, so that the direction of movement of the object will be determined by the manner in 70 which the housing and moving member are placed between the object to be moved and an immovable part.

My improved device is heavily constructed and is arranged to be formed of cast 75 steel. It is of great strength and compactly arranged and of few parts.

The front wall and bottom wall of the housing are provided with a recess 61, in which a crow-bar, spike, or other position-retaining device may be received when desired, this recess being in line with the longitudinal axis of the device.

Having thus fully described my invention, what I claim as new and desire to secure by Letters Patent, is:

A moving implement comprising a housing having a front wall and rearwardly extending side-walls terminating in rearwardly and inwardly slanting wings projecting toward each other for forming a slide-guide space extending longitudinally in the housing, a slide provided with a rear wall and forwardly projecting flanges and having a web between said flanges spanning the space between said wings, said slide having rear rearwardly and inwardly projecting faces projecting toward each other and coacting with said wings, said forwardly projecting flanges on said slide and said side walls of said housing arranged for forming a space extending longitudinally between said housing and slide, a tooth-rack on said slide in said space and spaced from said front wall, the front wall of said housing provided with a slot, a segment-gear pivoted to said housing and extending through said slot and into said longitudinally extending space into engagement with the teeth of said rack, a pawl pivoted to said housing and extending into said space into engagement with the teeth of said rack, and a moving bar for moving said slide extending from said segment-gear.

In testimony whereof, I have hereunto signed my name in the presence of two subscribing witnesses.

HARRY W. MCKEE.
